(57) **CLAIM**

The ornamental design for an archery bow cable yoke, as shown and described.

DESCRIPTION

FIG. 1 is an angled isometric view of the archery bow cable yoke.

FIG. 2 is another angled isometric view of the archery bow cable yoke.

FIG. 3 is a front view of the archery bow cable yoke.

FIG. 4 is a back view of the archery bow cable yoke.

FIG. 5 is a left side view of the archery bow cable yoke.

FIG. 6 is a right side view of the archery bow cable yoke.

FIG. 7 is a top view of the archery bow cable yoke; and,

FIG. 8 is a bottom view of the archery bow cable yoke.

The broken lines in the Figures are for illustrative purposes only. The broken lines form no portion of the claimed design.
